US0D1101032S

(12) **United States Design Patent** (10) **Patent No.:** **US D1,101,032 S**
(45) **Date of Patent:** **** Nov. 4, 2025**

(54) **PRINTER**

(71) Applicant: **STAR MICRONICS CO., LTD.**,
Shizuoka (JP)

(72) Inventor: **Yusuke Sone**, Shizuoka (JP)

(73) Assignee: **STAR MICRONICS CO., LTD.**,
Shizuoka (JP)

(**) Term: **15 Years**

(21) Appl. No.: **29/849,248**

(22) Filed: **Aug. 9, 2022**

(30) **Foreign Application Priority Data**

Feb. 17, 2022 (JP) ..... 2022-003036 D
Feb. 17, 2022 (JP) ..... 2022-003037 D

CLAIM

The ornamental design for a printer as shown and described.

DESCRIPTION

FIG. 1 is a perspective view 1 (the first embodiment).

FIG. 2 is a perspective view 2 (the first embodiment).

FIG. 3 is a front view (the first embodiment).

FIG. 4 is a rear view (the first embodiment).

FIG. 5 is a left side view (the first embodiment).

FIG. 6 is a right side view (the first embodiment).

FIG. 7 is a top view (the first embodiment).

FIG. 8 is a bottom view (the first embodiment).

FIG. 9 is a perspective view 1 (the second embodiment).

FIG. 10 is a perspective view 2 (the second embodiment).

FIG. 11 is a front view 2 (the second embodiment).

FIG. 12 is a rear view (the second embodiment).

FIG. 13 is a left side view (the second embodiment).

FIG. 14 is a right side view (the second embodiment).

FIG. 15 is a top view (the second embodiment); and,

FIG. 16 is a bottom view (the second embodiment).

The features shown in broken lines in the drawings illustrate portions of the printer that form no part of the claimed design.

1 Claim, 16 Drawing Sheets
